UNITED STATES PATENT OFFICE.

JOHN F. BARKER, OF SPRINGFIELD, MASSACHUSETTS, ASSIGNOR TO GILBERT & BARKER MANUFACTURING COMPANY, OF SPRINGFIELD, MASSACHUSETTS, A CORPORATION.

HYDROCARBON-BURNER.

No. 893,599.

Specification of Letters Patent.

Patented July 21, 1908.

Application filed August 30, 1907. Serial No. 390,708.

To all whom it may concern:

Be it known that I, JOHN F. BARKER, a citizen of the United States of America, residing at Springfield, in the county of Hampden and State of Massachusetts have invented new and useful Improvements in Hydrocarbon-Burners, of which the following is a specification.

My present invention relates to improvements in hydrocarbon burners and of the type known as the multi-jet fuel oil burners.

One of the objects of invention is to provide a structure in which the oil nozzles are so arranged with relation to the air jets that complete oxygenization and thorough mixing of the particles of oil will be effected, and, without any danger of extinguishment of the flames by the air pressure.

A further object of the invention is to provide a structure in which the oil nozzles, and consequently the flames, are symmetrically arranged at the end of the burner. With these and other objects in view, further advantages will be referred to in the body of the specification and particularly pointed out in the claims.

It is a well known fact in the use of jet oil fuel burners, that the finer the particles of oil are subdivided by the aspirating or carbureting action of the air under pressure, the more perfect will be the combustion, and, at the same time a smaller quantity of the liquid fuel will be required to produce a given temperature. These two considerations are most important in the use of jet fuel oil burners, as I have found by repeated trials and experiments.

In tempering, say a piece of polished metal, if free oxygen is present the metal will be tarnished or darkened producing what is known as "scale" or burning the metal which is undergoing the process of tempering or annealing. My present invention, is designed to overcome these serious defects, and, as stated above I have found by trial and experiment to effectually accomplish these results by my improvements which will be fully set forth in the body of the specification.

Referring to the drawings which form a part of this application, Figure 1 is a longitudinal sectional view of the complete burner showing the relative location and arrangement of the parts. Fig. 2 is a detailed perspective view of the atomizing nozzles and

spider. Fig. 3 is a detailed perspective view of the plate which is arranged at the end of the air chamber and through which the atomizing nozzles extend, as shown in Fig. 1. Fig. 4 is an end elevation of the burner showing particularly the relative arrangement of the plate and nozzles.

Referring to the drawings in detail in which like characters designate the same element, *a* designates the main or body portion of the burner which is provided with an internal plate or diaphragm *b*, that divides the same into two chambers *c* and *d*. The chamber *c* being the receiving chamber for the oil through a suitable inlet opening *e*, and the chamber *d* the air receiving chamber through a suitable opening *f*. Connected to the main body portion *a*, by means of the threads *g* is a barrel element *h*, in the outer end of which are, arranged the atomizing nozzles, and the spider *i* having the series of radially extending arms *j* to which are secured by means of a threaded connection, as indicated at *k*, the atomizing nozzles *m*. These nozzles being preferably provided with a cone shaped surface *n* to insure a proper bearing or shoulder for the threaded portion *k*.

Extending from the diaphragm *b* to the spider *i* is a pipe *o* of suitable dimensions for conveying the oil to the spider and nozzles. The inlet end of the pipe *o* being controlled by means of the needle valve *p*, that is operated by means of the usual hand wheel *q*.

In the outer end of the barrel *h* is secured a plate *r* by means of screws *s* that pass through the wall of the barrel and into the edge of plate *r*, the receiving threads in the plate *r* being designated by the letter *t*. This plate is provided with a series of conical openings *u*, of suitable dimension, the larger end of the openings being arranged toward the inside of the barrel. Extending into the openings *u* are the oil fuel nozzles *m*, arranged concentrically within the openings *u*, their outer ends being arranged flush with the outer or face side of plate *r* as plainly indicated in Fig. 1 at *v*.

In the operation of the burner the oil and air are both forced in under pressure in the usual manner, the oil passing through the tube *o* to the several nozzles *m* by means of the radial passage-ways *w*, in the arms *j* of the spider, and at the same time the compressed air enters the interior of the main

- body portion *a* through the openings *f* and passes from thence through the barrel *h* around the arms *j* of the spider *i*, through the openings *u* in the plate *r* and issuing from these openings in close contact with the escaping oil from the nozzles *m*, whereby complete oxygenization and atomization of the liquid hydro-carbon is effected. The purpose of the conical-shaped openings *u* in the plate *r* is to allow a current of air under a fairly low pressure to be employed, which is a decided advantage since such an arrangement of air outlets will prevent the flame from being extinguished. It will be observed that the conical openings *u* in the plate *r* has the effect of directing the escaping air adjacent to the outer end of the nozzles as the air flows through the openings in the plate *r*.
- 20 By arranging the end of the nozzles *m* flush with the outer face of the plate *r* there is no possibility of any back pressure of the air acting on the end of the nozzles *m* and preventing the free escape of the liquid fuel, 25 as is the case sometimes where the nozzles are arranged back from the outer edge of end plate.

By employing a multiplicity of oil jets the escaping oil is thereby sub-divided into 30 several streams, with the result that by having the compressed air pass circumferentially around each nozzle through the conical openings *u* each jet is therefore subjected to an atomizing effect, whereas if only one jet for 35 oil were used for the same quantity of oil the atomizing effect on the oil would not be nearly as complete, but on the other hand would be carried as small globules into the furnace causing a waste of the oil and incomplete combustion of the same. A further 40 result in the use of multiple oil jets lies in the fact that should one or more of the jets be extinguished the remaining ones would immediately ignite the same, thus preventing 45 the complete extinguishment of the burner as is the frequent occurrence when only a single oil jet is employed.

The construction herein described permits the use of interchangeable plates *r* for various air pressures which is a great advantage 50 in this type of burner. This burner is primarily designed for a low air pressure, but is adapted for any of the air pressures now in

common use, and any of the systems already installed.

55

What I claim, is:—

1. In a hydro-carbon burner having in combination, a main body portion, a diaphragm dividing the same into two chambers, a barrel portion connected with the main body portion, a spider provided with passage-ways and communicating with one of said chambers, nozzles communicating with the passage-ways of the spider, and a plate provided with conical shaped openings carried by the barrel and into which the nozzles project, whereby upon the passage of the hydro-carbon liquid through the nozzles and atmospheric air under pressure through the conical-shaped openings in the plate, the liquid fuel will be atomized, as described.

2. In a device of the class described, in combination with the main body portion, a diaphragm therein dividing the same into two compartments, one of the compartments being the oil receiving compartment and the other the air receiving compartment, a barrel element connected to the main body portion and carrying a series of nozzles at its outer end, and communicating means between the nozzles and oil compartment; a removable plate located in the end of the barrel provided with openings for receiving the nozzles means for regulating the flow of oil through the communicating means, and means for deflecting the flow of air into close contact with the outer end of the nozzles, as described.

3. A multi-jet fuel burner having in combination, a main body portion, a diaphragm dividing the same into two compartments, a removable barrel secured to the main body portion, a plate removably secured in the end of the barrel, and provided with a plurality of conically shaped openings therein, nozzles entering said openings, and communicating means extending from one compartment of the main body portion to the nozzles, means for controlling the passageway through said communicating means, said nozzles being arranged flush with the outer end of the removable plate, as described.

JOHN F. BARKER.
